UNITED STATES PATENT OFFICE.

JOHN NEWBERRY REYNOLDS, OF GREENWICH, CONNECTICUT, ASSIGNOR, BY MESNE
ASSIGNMENTS, TO WESTERN ELECTRIC COMPANY, INCORPORATED, A CORPORATION
OF NEW YORK.

SWITCH-STOPPING MECHANISM.

1,184,020.

Specification of Letters Patent. Patented May 23, 1916.

Application filed January 29, 1915. Serial No. 5,023.

To all whom it may concern:

Be it known that I, JOHN NEWBERRY REYNOLDS, a citizen of the United States, residing at Greenwich, in the county of Fairfield 5 and State of Connecticut, have invented certain new and useful Improvements in Switch-Stopping Mechanism, of which the following is a full, clear, concise, and exact description.

10 This invention relates to stopping mechanism for automatic telephone switches, and in the present disclosures is shown applied to a switch of the panel type, although obviously it is equally applicable to switches 15 of other kinds.

The object of this invention is the provision of means whereby a switch carriage, moving at high speed, may be definitely stopped with the switch brushes centrally positioned on the desired set of contacts.

In the drawings, Figure 1 is a side elevation of the switch with parts broken away; Fig. 2 shows a section of the stopping device on the line 2--2 of Fig. 3; Fig. 3 is a 25 plan view of the structure shown in Fig. 2; Fig. 4 shows a section of a modification of the stopping device taken on the line 4--4 of Fig. 5; and Fig. 5 is a plan view of the structure shown in Fig. 4.

30 As the switch structure herein disclosed is in general the same as that shown in Patent No. 1,123,696, with the addition of the stopping device which forms the subject of this invention, the general structure 35 of the switch will be only briefly described.

The switch shown in Fig. 1 is of the panel type. This switch comprises a longitudinally movable shaft 1, having a plurality of sets 2, of brushes fixed thereto, only two 40 sets being shown in the drawings. Each set of brushes is adapted to traverse a section or group of trunk terminals 3. 4 represents a rotatable drum and 5 is an idler pulley, adapted through the medium of magnet 6, 45 to force the bar 7 into engagement with the power drum 4, whereby the shaft and brushes carried thereby are elevated. Carried by the shaft 1 is a plurality of interrupter brushes 8, which, in the movement of 50 the switch shaft, are caused to traverse the commutators or interrupters 9 whereby the operation of the switch is governed. The brushes of each set 2 are normally held from 55 engagement with the fixed terminal contacts by reason of the vertical arm of the bell-

crank trip lever 10 being positioned between the two innermost brushes of the set. A trip rod 11, actuated by the magnet 12, is provided. This rod carries a plurality of flexible fingers 13, which are positioned at 60 progressively increasing distances from the normal position of the horizontal arms 14 of the trip levers. Thus, if during the preliminary upward movement of the trunk shaft, the rod 11 is rotated, one of the fingers 13 will operatively engage its respective trip lever 14, while the remaining trip fingers will pass through the line of travel of their respective levers to the other side thereof. The set of brushes to be tripped 65 or released, therefore, depends upon the distance the shaft travels, and consequently on the number of segments of the lowermost left commutator traversed by its respective brush 8, prior to the energization of the 70 trip magnet 12. After the tripping of a set of brushes, the elevation of the shaft is continued either by the same power drum or by a high-speed drum, as described in the 75 above mentioned patent.

The return to normal may be accomplished 80 either by gravity, upon the release of the brush shaft, or by means of an independent drum similar to 4, which rotates in the opposite direction.

The bar 7, as shown in Figs. 2 and 4, is 85 provided with a series of perforations 15 which are spaced apart equal to the distances between adjacent terminals in the bank 3. Bar 7 passes adjacent to the idler 90 pulley 16 which has its central portion reduced as shown in Figs. 3 and 5. This pulley co-operates with the stopping mechanism on the opposite side of the shaft, and together therewith forms the subject of this 95 invention. The stopping mechanism primarily comprises a plunger or plate 18, which, when the switch has reached the desired position, is forced into the appropriate perforation 15, whereby the switch will be 100 stopped with the brushes centrally positioned on the set of contacts.

In the modification shown in Fig. 2, the plate 18 is formed as a horizontal arm of the bell crank lever 19 which is pivotally secured 105 by the pin 20 between the lugs 21 of the armature supporting plate 22. Plate 22 is pivotally supported at 23, and has secured thereto in any desired manner the armature 24 of the electromagnet 25. Armature 110

24 is provided with a lug 26 of copper or other non-magnetic material, so that the armature will be quickly retracted upon de-energization of the magnet. Secured be-
 5 tween the lug 27 carried by the frame mem-
 ber which forms the mounting for the mag-
 netic structures and the upper end of the
 bell crank lever 19 is a spring 28. This
 10 spring tends to normally maintain the ar-
 mature and parts carried thereby in a re-
 tracted position. It also tends to hold the
 plunger or plate 18 in contact with the
 roller 29. Thus, if while the bar 7 is being
 15 moved rapidly upward by a drum such as
 4, the electromagnet 25 is deenergized. The
 plunger 18 will be forced outward and the
 end thereof will pass through one of the per-
 20 forations 15. If the shaft is moving at a
 high speed, the momentum thereof will
 cause the plate 18 to be carried upwardly
 against the tension of the spring 28. A
 25 screw 30, projecting downwardly from the
 lug 27 is provided to limit this upward
 movement. Ordinarily, however, the over-
 throw will not be sufficient to carry the plate
 30 18 into engagement with the screw 30. Af-
 ter this overthrow, the plate or plunger 18
 will be immediately returned to its normal
 position in engagement with roller 29 by
 35 means of the tension of spring 28. It is of
 course understood that the electromagnet 25
 is in an energized condition during the
 movement of the switch shaft and that in
 stopping current is cut off from the drive
 40 clutch magnet as 6 at the same instant as
 from the stop magnet 25.

The modification shown in Fig. 4 has ex-
 45 actly the same function as the structure
 shown in Fig. 2, but differs therefrom some-
 what as to structural details. In this modi-
 fication the plunger 31 is pivotally supported
 50 between the in-turned edges of the plate 32
 which is pivotally supported on the pin 33
 carried by the supporting frame work. The
 plunger 31 is held in position against the
 55 roller 29 by means of the spring 34 secured
 at its lower end to the pin 33, supported
 between the edges of the plate 32, and at its
 upper end to a member 36 adjustably se-
 cured to the plunger 31. The armature 37
 60 is pivotally mounted on the pin 33. Pro-
 jecting from the plate 32 is a screw-threaded
 stud 38 which extends through the perfo-
 rated upper end of the armature 37. The
 armature 37 is held in adjustable spaced re-
 65 lation to the plate 32 by means of the spring
 39, surrounding the stud 38 between the ar-
 mature and said plate and the nuts 40 on the
 opposite side of the armature. The ar-
 mature is normally held in retracted position
 70 by means of the spring 41 secured at one
 end to the lug 42 carried by the frame, and
 at the other end to the member 43, adjust-
 ably secured to the plate 32. The outward
 75 or retractile movement of the armature is

limited by means of the pin 44 carried by
 the supporting frame.

By means of the invention above de-
 scribed, a switch may be operated at a very
 high rate of speed and the brushes positively
 70 stopped and centrally positioned on the de-
 sired set of contacts without excessive jar
 or pounding. For while the positioning of
 the plunger in the perforation 15, corre-
 sponding to the desired stationary contacts,
 75 insures that the brushes will be centrally
 positioned on said contact, temporary over-
 run is permitted by means of the spring 28
 in Fig. 2 and spring 34 in Fig. 4, but this
 overrun is immediately corrected by the ac-
 80 tion of the springs in returning the member
 18 into engagement with the roller 29.

As it is obvious that many modifications
 may be made in my invention, without de-
 parting from the spirit thereof, I desire it
 85 understood that my invention shall be lim-
 ited merely by the scope of the following
 claims.

What is claimed is:

1. In a telephone switch, a support, 90
 brushes thereon, a row of sets of contacts,
 means for moving said support to cause said
 brushes to traverse said contacts, a series of
 recesses in said support spaced apart dis-
 95 tances equal to the distances between cor-
 responding contacts of said row, and a
 plunger for engagement with any one of
 said recesses to positively stop forward
 movement of the brushes on the correspond-
 ing set of contacts.

2. In a telephone switch, a shaft, a brush
 thereon, a row of contacts, means for mov-
 ing said shaft longitudinally to cause said
 brush to traverse said contacts, a series of
 recesses in said shaft corresponding to the
 105 contacts of said row, and a member for en-
 gagement with any one of said recesses to
 stop the forward movement of said shaft
 with the brushes thereof in engagement with
 a desired contact.

3. In a telephone switch, a support,
 brushes thereon, a row of contacts, means
 for moving said support to cause said
 brushes to traverse said contacts, a series
 of recesses in said support spaced apart
 115 distances equal to the distances between cor-
 responding contacts of said rows, a member
 for engagement with any one of said re-
 cesses to positively stop forward movement
 of the support with the brushes on the cor-
 120 responding set of contacts, a tension device
 tending to maintain said member in its op-
 erative position, and an electromagnet for
 moving said member to its inoperative po-
 sition.

4. In a telephone switch, a support,
 brushes thereon, a row of sets of contacts,
 means for moving said support to cause
 said brushes to traverse said contacts, a se-
 ries of recesses in said support correspond-
 125

ing to the sets of contacts in said row, a plunger for engagement with any one of said recesses to positively stop forward movement of the brushes on the corresponding set of contacts, a stop for preventing movement of said plunger beyond its normal position in one direction but allowing it to be moved in the direction of forward movement of said shaft, and a tension device tending to maintain said member in engagement with said stop.

5. In a telephone switch, a shaft, brushes thereon, a row of sets of contacts, means for moving said shaft to cause said 15 brushes to traverse said contacts, a series of recesses in said shaft corresponding to the contact sets of said row, a member for engagement with any one of said recesses to stop the forward movement of said shaft, 20 a stop for preventing movement of said member beyond its normal position in one direction but allowing it to be moved in the direction of forward movement of said switch, an electromagnet for moving said 25 member to inoperative position and a tension device tending to maintain said member in its operative position and in engagement with said stop.

6. In a telephone switch, a support, brushes thereon, a row of sets of contacts, 30 means for moving said support to cause said brushes to traverse said contacts, a series of recesses in said support corresponding to the sets of contacts in said row, an electromagnet, an armature for said magnet, 35 a bell crank lever pivotally secured to said armature, a plunger formed as one arm of said bell crank and arranged for engagement with said recesses when said armature is retracted, a stop for preventing 40 movement of said member beyond its normal position in one direction but allowing it to be moved in the direction of forward movement of said switch and a tension device acting on the other arm of said bell 45 crank to normally maintain said armature retracted and said plunger in engagement with said stop.

In witness whereof, I hereunto subscribe my name this 28th day of January, A. D. 50 1915.

JOHN NEWBERRY REYNOLDS.
